UNITED STATES PATENT OFFICE.

JAMES E. BANCROFT, OF TOLEDO, OHIO.

HYDROCARBON-BURNER.

SPECIFICATION forming part of Letters Patent No. 738,755, dated September 15, 1903.

Application filed April 22, 1903. Serial No. 153,730. (No model.)

To all whom it may concern:

Be it known that I, JAMES E. BANCROFT, a citizen of the United States, residing at Toledo, Lucas county, Ohio, have invented a new and useful Hydrocarbon-Burner, of which the following is a full and exact specification.

My invention relates to a hydrocarbon-burner, and has for its object to provide an inexpensive burner having an extensive vaporizing-duct which is exposed to heat in compact form and all parts of which are readily accessible for removing therefrom any deposit or sediment produced by vaporizing liquid hydrocarbon.

15 The object of my invention is accomplished as hereinafter described, and illustrated in the drawings, in which—

Figure 1 is a part section and part elevation of a burner constructed in accordance with 20 my invention. Fig. 2 is an elevation of the grooved plug, showing the slot for the valve-stem.

The body 1 of the burner is arranged in 25 elongated form and provided with a conical bore 2, extending axially through the body from end to end. The burner-body is also provided with integral bosses 3 and 4, which are located diametrically opposite each other some distance inward from the small end 5.

30 Within the boss 3 there is formed a chamber 6, the bottom of which is arranged to seat a needle-valve 7, which is adapted to control the outlet-port 8, extending outward from chamber 6. The needle-valve is threaded in 35 the boss 4, the free end of which is threaded to receive a packing-gland 9. Within the bore of the burner-body there is housed a plug 10, conforming to the conical formation of the bore and having a groove 11 of suitable

40 width and depth. The groove extends in the form of a helix from the large end to the small end of the plug, and when inserted into the conical bore the plug 10 and the body 1 jointly form a duct 12, which, being in the 45 form of a helix, is therefore adapted to expose a considerable column of liquid hydrocarbon to heat for vaporization without materially increasing the size of the burner.

Valve-chamber 6 is located between two coils of the helix, and as the groove 11 is extended beyond the valve-chamber 6 the groove 11 is returned to the chamber 6 to form a duct 13, intersecting chamber 6, as shown in Fig. 1. The pitch of the helix is also altered around valve-chamber 6 to provide the 50 plug with a diametric slot 14 without intersecting the groove 11. The diametrically-reduced portion 15 of the valve-stem is extended through the slot, and to allow for adjustable movement of the plug the slot 14 is slightly 55 elongated lengthwise of the plug.

The plug 10 is drawn and held in position within the bore 2 by means of a nut 16, run upon the threaded end 17 of the plug 10, and to prevent the plug 10 from turning while 60 the threaded end 17 is drawn into the nut 16 the large end of the plug 10 is preferably provided with a squared shoulder 18 for applying a wrench thereto to hold the plug. To attach the burner to a supply-pipe 19, the 65 body portion 1 is preferably provided with an integral squared section 20 and an integral coupling 21.

A burner thus constructed and coupled to a supply-pipe will rapidly vaporize hydrocarbons within the duct 12, and by detaching the burner from the supply-pipe and removing the needle-valve the conical plug 10 may be readily withdrawn from the body 1 and the groove quickly cleaned from deposits and 70 sediment produced by vaporizing liquid hydrocarbons. The plug 10 may be grooved in any suitable manner without departing from the spirit of my invention.

What I claim as my invention, and desire 75 to secure by Letters Patent, is—

In a hydrocarbon-burner, an elongated burner-body arranged in the form of a tube having a contracted end and an outlet-port formed near the contracted end of the tube 80 provided with a valve extending diametrically through the body, a plug inserted into the body and coupled thereto at the contracted end and slotted diametrically to receive the valve, a channel formed upon the surface 85 of the plug extending from the large end, in

helical direction, toward the small end, with the coils of the helical groove arranged to clear the slot for the valve and connect in the reverse direction with the outlet-port, and
5 means to couple a supply-pipe to the burner-body.

In testimony whereof I have signed my

name to this specification in the presence of two subscribing witnesses.

JAMES E. BANCROFT.
